R. A. McCANN

RAILWAY TRAFFIC CONTROLLING APPARATUS

Filed May 15, 1924

UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 15, 1924. Serial No. 713,453.

To all whom it may concern:

Be it known that I, RONALD A. McCANN, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing means controlled by energy received from the trackway.

Apparatus embodying my invention is particularly adapted for use on two or more parallel tracks where it is desirable, for purposes of safety, to limit the number of trains which may simultaneously occupy a given territory, such for example, as the territory in the middle of a bridge span, a railway station, or a "gauntlet track."

I will describe two forms and arrangements of apparatus embodying my invention, and will then point out the novel features thereof in claims.

In the accompanying drawing, Fig. 1 is a diagrammatic view showing one form of trackway apparatus embodying my invention. Fig. 2 is a diagrammatic view showing a modification of the apparatus shown in Fig. 1 and also embodying my invention.

Similar reference characters refer to similar parts in both views.

Referring first to Fig. 1, the reference characters 1 and 1^a designate the track rails of a stretch of railroad track X, and the reference characters 2 and 2^a designate the two rails of a second track Y, parallel with track X. These two tracks comprise a restricted territory which should be occupied by but one train at a time, and as here shown this restricted territory is formed by a gauntlet made up of the two tracks.

As here shown, traffic normally moves over each track X and Y in the direction indicated by the arrow, and the rails of each track are divided into a plurality of successive track sections by means of insulated joints 3. Only one section A—B of track X and one section C—D of track Y are shown in the drawing, and the gauntlet portion is located within these sections.

Each section of each track is provided with a trackway signal designated by the

reference character S with an exponent corresponding to the location. Each such signal S is here shown as a three-position semaphore signal located adjacent the entrance end of the associated section, though this particular form and location are not essential. These signals are controlled in the usual and well known manner by means responsive to traffic conditions in advance by means forming no part of my present invention and hence omitted from the drawing for the sake of simplicity. It is sufficient to say that each signal is controlled so that when the associated section is occupied, the signal indicates stop; when the corresponding section is unoccupied and the next section in advance is occupied, the signal indicates caution; and when the corresponding section and the section next in advance are both unoccupied, the signal indicates proceed.

Each of the signals S^a and S^c is provided with a circuit controller designated by the reference character K with a suitable exponent arranged to be closed when the corresponding signal indicates proceed or caution, but to be open when such signal indicates stop.

Each section is also provided with a track circuit including a track relay designated by the reference character R with a suitable distinguishing exponent and connected across the rails adjacent the entrance end of the section and a suitable source of track circuit current here shown as a track battery designated by the reference character G with an appropriate exponent and connected across the rails adjacent the exit end of the section. To complete and isolate these track circuits the frogs formed where rail 1^a crosses rail 2 are separated from the rest of rail 1^a by means of insulated joints 3^a and rail 1^a is made electrically continuous past the breaks so formed, by means of auxiliary cables 4.

Means are also provided for supplying to each section an alternating train controlling current. For this purpose I provide each of sections A—B and C—D with a track transformer designated by the reference character T with an exponent corresponding to the location and having a secondary winding 5 interposed between one rail of the associated section and the correspond-

ing track battery G. An impedance 7 is interposed between the secondary 5 of each track transformer and one rail of the corresponding section in the usual manner.

5 Alternating current is at times supplied to transformers T^A and T^C from a transformer Q, the primary 9 of which is constantly supplied with alternating current from some suitable source not shown in the

10 drawing.

The primary circuit for transformer T^C is closed when relay R^B is energized and signal S^C indicates proceed or caution, under which conditions current flows from the 15 secondary 8 of transformer Q, through wire 10, front contact 11 of track relay R^B , wire 12, circuit controller K^C , operated by signal S^C , wire 13, primary 6 of transformer T^C , and wires 14 and 15 back to secondary 8 20 of transformer Q.

When relay R^D is energized and signal S^A indicates proceed or caution, current is supplied to transformer T^A over a circuit which may be traced from secondary 8 of 25 transformer Q, through wires 10 and 16, front contact 17 of relay R^D , wire 18, circuit controller K^A operated by signal S^A , wire 18, primary 6 of transformer T^A , and wire 15 back to secondary 8 of transformer Q.

30 Before explaining the operation of the apparatus it should be pointed out that the trackway apparatus shown in Fig. 1 is intended for co-operation with train carried governing means in such manner that when 35 the train occupies a stretch of track which is supplied with alternating train controlling current a proceed indication is received on board the train, but when such supply is interrupted a stop indication is received 40 on the train.

As shown in the drawing both signals S^A and S^C are indicating proceed and both sections A—B and C—D are unoccupied. Relays R^D and R^B are therefore both energized by current from the associated track 45 batteries G. As a result, transformers T^A and T^C are both supplied with alternating current and sections A—B and C—D are each supplied with train controlling current.

50 I will now assume that a train on track X enters section A—B. Relay R^B is de-energized as soon as the train passes point B. The circuit for transformer T^C is therefore interrupted and the supply of train controlling current to section C—D is therefore discontinued. A train entering section C—D would therefore receive a stop indication. The de-energization of relay 55 R^B does not affect the supply of train governing current to section A—B, and so the first train is permitted to proceed through the section under a proceed indication. As the train enters the section to the left of point A, signal S^A moves to the stop position. The circuit is then interrupted for

transformer T^A , thus causing a following train entering section A—B on track X to receive a stop indication. As the first train moves out of section A—B, if section A—B is unoccupied, relay R^B becomes energized, 70 thus completing the circuit for transformer T^C , so that another train on track Y entering section C—D would receive a proceed indication.

In the modification shown in Fig. 2, the 75 track relays R^D and R^B are alternating current relays, and the transformers T^A and T^C constitute sources of track circuit current as well as of train controlling current.

Means are also provided for supplying to 80 the rails in parallel of sections A—B and C—D, a current which I shall hereinafter term a "loop" current. For this purpose I provide each of these sections with an impedance 85 connected across the rails adjacent the exit end of the section, and a similar impedance 20 connected across the rails adjacent the entrance end of the section. The connections for the loop circuit are then made to the mid-points of these 90 impedances. Loop current is supplied to each of the sections A—B and C—D by a loop transformer associated with such section and designated by the reference character L with an exponent corresponding to 95 the location. The primary 22 of each loop transformer is constantly supplied with alternating current from secondary 8 of transformer Q.

The loop circuit for section C—D may be 100 traced from secondary 21 of transformer L^C , through wire 23, front contact 24 of relay R^B , wire 25, impedance 20 in section C—D, through the rails of the section in parallel to impedance 19, wire 26, circuit controller 105 K^C operated by signal S^C , and wire 27 back to transformer L^C . This circuit is closed only when relay R^B is energized and signal S^C indicates proceed or caution, under which conditions loop current is supplied to section 110 C—D. When signal S^A is at proceed or caution and relay R^D is energized, current flows from secondary 21 of loop transformer L^A , through wire 28, front contact 29 of relay R^D , wire 30, impedance 20 in section 115 A—B, through both rails of the section in parallel to impedance 19, wire 31, circuit controller K^A operated by signal S^A , and wire 32 back to transformer L^A . Under these conditions loop current is supplied to 120 the rails of section A—B.

The trackway apparatus shown in Fig. 2 is intended for co-operation with train carried governing means so arranged that when 125 the train occupies a section of track that is supplied with alternating track circuit current and also with loop current the train receives a proceed indication, but when the supply of either of such currents is interrupted, the train receives a stop indication. 130

Track circuit is at all times supplied to both sections. It will be noticed however that when a train occupies section A—B, the resulting de-energization of relay R^B 5 causes the loop current to be discontinued in section C—D and hence will cause a stop indication to be received by a train in section C—D. Similarly, a train in section C—D will cause a stop indication on a train 10 in section A—B.

If a train is occupying one of the sections shown in the drawing, such as section A—B, a second train following the first into the section will be deprived of track circuit 15 current as a result of the shunting action of the wheels and axles of the first train and hence the second train will receive a stop indication.

It should also be pointed out that when 20 either of signals S^A or S^C is at stop, the opening of the corresponding loop circuit will cause a stop indication on a train proceeding through the gauntlet on the associated track.

25 It will be plain that, with both forms of apparatus embodying my invention, a train in either of the sections A—B or B—C will cause a stop indication to be received on a train occupying the other section.

30 Although I have herein shown and described only one form of trackway apparatus embodying my invention, it is understood that various changes and modifications may be made therein within the scope of 35 the appended claims without departing from the spirit and scope of my invention.

Having thus described my invention, what I claim is:

40 1. In combination, two parallel sections of railway track comprising a restricted territory, means for connecting a source of train controlling current across the rails of each section, and means for interrupting the supply of such current to each section when the other section is occupied.

45 2. In combination, two parallel sections of railway track comprising a restricted territory, means for supplying train controlling current to each section, a track circuit for each section including a source of track circuit current and a track relay, and means for interrupting the supply of such train controlling current to each section when the other section is occupied.

50 55 3. In combination, two parallel sections of railway track comprising a restricted territory, means for supplying train controlling current to each section, a track circuit for each section including a source of track circuit current and a track relay, and means controlled by each track relay and arranged when the corresponding section is occupied for interrupting the supply of train controlling current to the other section.

60 65 4. In combination, two parallel sections

of railway track, a track circuit for each section including a track relay and a source of track circuit current, means for supplying each section with train controlling current, and means for one section controlled by 70 traffic conditions in the other section for at times interrupting the supply of train controlling current to said one section.

5. In combination, two parallel sections of railway tract, a track circuit for each 75 section including a track relay and a source of track circuit current, a transformer for supplying train controlling current to one of said sections, and means responsive to traffic conditions in the other section for 80 controlling the supply of current to said transformer.

6. In combination, two parallel sections of railway track, a track circuit for each section including a track relay and a source of 85 track circuit current, and a transformer controlled by the track relay for one of said sections for supplying train controlling current to the other section.

7. In combination, two parallel sections 90 of railway track comprising a restricted territory, means controlled by traffic conditions in advance for supplying each section with train controlling current, and means for each section responsive to traffic 95 conditions in said section for at times interrupting the supply of train controlling current to the other section.

8. In combination, two parallel sections of railway track comprising a restricted territory, a source of track circuit current for each 100 section, a track transformer for each section connected across the rails of the section and controlled by traffic conditions in advance, and means for each section responsive to 105 traffic conditions in the associated section for at times controlling the track transformer for the other section.

9. In combination, two parallel sections of railway track comprising a restricted 110 territory, means for constantly supplying alternating track circuit current across the rails of each section, track relays for each section connected across the rails of the corresponding section, and means controlled by 115 each track relay for at times supplying loop current to the rails of the other section.

10. In combination, two parallel sections of railway track, a separate source of alternating track circuit current constantly 120 connected across the rails of each section, a track relay connected across the rails of each section, means for supplying loop current to each section, and means controlled by the track relay for each section for at times 125 interrupting the supply of loop current to the rails of the other section.

11. In combination, two parallel sections of railway track, a separate source of alternating track circuit current constantly con- 130

5 nected with the rails of each section, means for supplying loop current to each section, and means controlled by the track relay for each section for at times interrupting the supply of loop current to the rails of the other section.

12. In combination, two parallel sections of railway track, means for supplying track circuit current to one section, and means responsive to traffic conditions in the other section for at times supplying loop current to said one section.

13. In combination, two parallel sections of railway track comprising a restricted territory, a source of alternating current for each section constantly connected across the rails of the section, a track relay for each section connected across the rails of such section, means for each section controlled by traffic conditions in advance of the section for supplying loop current to the section, and means controlled by each track relay for at times interrupting the supply of loop current to the other section.

25 14. In combination, two parallel sections of railway track comprising a restricted territory, a source of alternating current for each section constantly connected across the rails of the section, a track relay for each section connected across the rails of such section, means for each section controlled by traffic conditions in advance of the section for supplying loop current to the section, and means controlled by each track relay and arranged when the associated section is occupied to interrupt the supply of loop current to the other section.

40 15. In combination, two parallel sections of railway track comprising a restricted territory, a track circuit for each section, and a train controlling circuit for each section including at least one rail of the section and controlled by traffic conditions in the other section.

45 16. In combination, two parallel sections of railway track comprising a restricted

territory, means for supplying alternating track circuit current to each section, and a loop circuit for each section including at least one rail of the associated section and controlled in response to traffic conditions in the other section.

17. In combination, two parallel stretches of railway track, a restricted territory thereon, a track circuit for each track, and means for each track controlled by traffic conditions on the other track within said territory for supplying train controlling current to the associated track.

18. In combination, two parallel stretches of railway track, a restricted territory containing at least a part of each stretch, a track circuit for each stretch, means for supplying train controlling current to each stretch, and means for interrupting the supply of such current to each stretch when a train occupies the other stretch within the limits of the restricted territory.

19. In combination, a railway having two parallel tracks, a restricted territory containing parts of both tracks, a track circuit for each track, means for supplying train controlling current to the rails of each section for controlling trains through said restricted territory, and means responsive to traffic conditions on one track within the limits of said territory for controlling the supply of train controlling current to that portion of the other track within the limits of said territory.

20. In combination, two parallel sections of railway track comprising a restricted territory, a train controlling loop circuit for each section including a source of current the terminals of which are connected with at least one rail adjacent the two ends of the section, and means for interrupting the loop circuit for each section when the other section is occupied.

In testimony whereof I affix my signature.

RONALD A. McCANN,
